Primary Examiner — Sandra Snapp*Assistant Examiner* — Altaira J Swangin(74) *Attorney, Agent, or Firm* — Novoclaims Patent Services LLC; Mei Lin Wong(57) **CLAIM**

The ornamental design for a divided snack bowl, as shown and described.

DESCRIPTION

FIG. 1 is a top perspective view of a divided snack bowl showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another top perspective view thereof, showing the divided snack bowl covered by a lid.

The broken lines depict portions of the divided snack bowl that form no part of the claimed design.

1 Claim, 9 Drawing Sheets(56)
